UNITED STATES PATENT OFFICE.

GEORGE B. THOMAS, OF BRIDGEPORT, CONNECTICUT, ASSIGNOR TO THE BEYANT ELECTRIC COMPANY, OF BRIDGEPORT, CONNECTICUT, A CORPORATION OF CONNECTICUT.

ELECTRIC SWITCH.

1,270,671.

Specification of Letters Patent. Patented June 25, 1918.

Application filed December 6, 1915. Serial No. 65,364.

To all whom it may concern:

Be it known that I, GEORGE B. THOMAS, a citizen of the United States of America, residing in the city of Bridgeport, county of 5 Fairfield, and State of Connecticut, have invented a certain new and useful Improved Electric Switch, of which the following is a specification.

My invention relates to electric switches 10 and particularly to a switch mechanism adapted for use in electric sockets, pendent switches and the like.

The object of my invention is to provide a simple and efficient mechanism adapted to 15 be operated by a pair of substantially aligned reciprocating push buttons.

In the accompanying drawings,

Figure 1 is a transverse section on the line 1—1, Fig. 2, through a pendent switch 20 in which my invention is embodied in one form;

Fig. 2 is a vertical section through this switch mechanism;

Fig. 3 is a detached perspective of the 25 switch frame and operating parts; and

Fig. 4 is a perspective of the wire terminal and its associated switch terminal.

While my invention may be embodied in switches of various types I have for the 30 sake of illustration shown it in the accompanying drawings in a pendent switch comprising a casing having shell 10 and cap 11 latched together in any suitable fashion. Contained within it is the insulating body 35 of the switch, which is here shown in two parts 12 and 13. These insulating buttons are recessed on their meeting faces to afford a switch chamber 14 into which extend the switch terminals 15 and 16 from 40 the wire terminals 17 and 18 on opposite sides of the switch body. These wire terminals form standards secured to the respective buttons by screws 19 and 20, this rigidly uniting the buttons together. The switch 45 terminals 15 and 16 are preferably of spring sheet metal independent of the wire terminals, and provided with base flanges 21 underlying the base flanges of the standards and thus in electrical and mechanical engagement with the latter.

The switch mechanism within the chamber 14 is carried by a frame 22 struck from sheet metal and secured to the lower button 13 by the screws 23. The ends of the

frame are angled upwardly and grooved at 45 24 to form guide-ways for the push buttons 25 and 26 at opposite ends of the push plate 27. The intermediate portion of the frame is centrally and longitudinally slotted at 28 and is provided with bearing lugs 29 50 on opposite sides of the slot and also up-standing pairs of stop lugs 30 and 31. The push plate 27 is of substantially the same width as the body of the frame and has a depressed portion 32 centrally slotted at 33 55 and provided with a cross-pin 34 within the slot. In the assembled position of the parts the slot 33 in the push plate registers with the slot 28 in the frame. The yoke-shaped switch piece 35 is pivoted at its open end on 60 the lugs 29 of the frame. Its bridge is perforated at 36 to permit the stem 37 of the spring pin to pass therethrough. The lower end of the spring pin forms an enlarged head 38 slotted at 39 to receive the cross-pin 70 34 of the push plate 27. Between the shoulders 40 and the head of the spring pin and the bridge of the switch yoke 35 is confined the operating coil spring 41.

The operation of the switch mechanism 80 is readily understood. Assuming the switch to be in the "off" position shown in Figs. 1 and 2, the switch piece 35 lies against the stop lugs 31 on the switch frame and is held firmly in this position by the pressure of 85 the switch spring 41 inasmuch as the push plate which carries the spring pin 37 is held against further displacement by the impingement of its stop lugs 42 against the opposite face of the stops 31 on the frame. 90 If now the push button 25 be displaced inwardly the head 38 of the push pin is carried with the push plate past the axis of oscillation of the switch piece formed by the lugs 29 on the frame, traveling during this 95 movement in the slot 28 in the frame. Immediately the spring 41, which has been further compressed by this movement, throws the switch yoke in the opposite direction until it impinges against the stops 30 100 on the switch frame. In this position the switch piece spans the switch terminals 15 and 16 and establishes the circuit through the switch.

The mechanism is rugged and serviceable 105 and affords a wide break between the switch terminals 15 and 16, thus affording a switch of high capacity while at the same time of

small size. The various portions of the switch mechanism may be stamped from sheet metal and bent to shape very economically so that the switch may be cheaply made. The assembly of the parts is extremely simple and there is no tendency of the mechanism to fly apart upon the separation of the insulating buttons 12 and 13 which form the insulating body of the 10 switch.

Various modifications of structure and arrangement of the parts will readily suggest themselves to others skilled in the art, particularly in adapting the switch for use in 15 connection with the fittings of various other types, without, however, departing from what I claim as my invention.

I claim as my invention:

1. In an electric switch, a switch frame, 20 an oscillating switch piece pivoted thereon, a reciprocating plate in sliding contact with the switch frame, a spring abutment moving therewith, a switch spring under compression between said abutment and the free end 25 of the oscillating switch piece and means for displacing said reciprocating plate to shift the abutment end of the switch spring from one side to the other of the axis of oscillation of the switch piece.
2. In an electric switch, a switch frame, 30 an oscillating switch piece pivoted thereon, a reciprocating plate in sliding contact with the switch frame, a spring abutment moving therewith, a switch spring under compression 35 between said abutment and the free end of the oscillating switch piece and means for displacing said reciprocating plate to shift the abutment end of the switch spring from one side to the other of the axis of 40 oscillation of the switch piece, together with means for limiting the extent of movement of said reciprocating plate.
3. In an electric switch, a switch frame, 45 an oscillating switch piece pivoted thereon, a reciprocating plate in sliding contact with the switch frame, a spring abutment moving therewith, a switch spring under compression 50 between said abutment and the free end of the oscillating switch piece and means for displacing said reciprocating plate to shift the abutment end of the switch spring from one side to the other of the axis of 55 oscillation of the switch piece, together with

means for limiting the extent of oscillation of the switch piece.

4. In an electric switch, a switch frame having a longitudinal slot, an oscillating switch piece pivoted in said frame, a reciprocating plate in sliding engagement with said switch frame and longitudinally slotted 60 in register with the slot in the latter and having a cross pin in said slot, a switch operating spring and a guide pin for said spring engaging the switch piece at one end and having a head pivoted on the cross pin 65 of said reciprocating plate, together with means for displacing said reciprocating plate to shift the head of said guide pin from one side to the other of the axis of oscillation of the switch piece.

5. In an electric switch, a switch frame having a longitudinal slot, an oscillating switch piece pivoted in said frame, a reciprocating plate in sliding engagement with said switch frame and longitudinally slotted 75 in register with the slot in the latter and having a cross pin in said slot, a switch operating spring and a guide pin for said spring engaging the switch piece at one end and having a head pivoted on the cross pin 80 of said reciprocating plate, together with means for displacing said reciprocating plate to shift the head of said guide pin from one side to the other of the axis of 85 oscillation of the switch piece, the head of said spring guide pin having shoulders against which one end of the switch spring abuts.

6. In an electric switch, a switch frame having at its opposite ends upstanding webs 90 grooved to form guide ways, and intermediate said end webs two pairs of lateral upstanding lugs forming stops, a pair of lateral bearing lugs projecting from opposite sides of the frame between the pairs of 95 stops, the body of the frame being longitudinally slotted between said bearing lugs substantially as described.

In testimony whereof I have signed my name to this specification, in the presence 100 of two subscribing witnesses.

GEORGE B. THOMAS.
